UNITED STATES PATENT OFFICE.

FRANCIS M. VAN ETEN, OF BUFFALO, NEW YORK.

DESIGN FOR A SPOON.

42,935.

Specification for Design.

Patented Aug. 27, 1912.

Application filed June 12, 1912. Serial No. 703,309. Term of patent 3½ years.

To all whom it may concern:

Be it known that I, FRANCIS M. VAN ETEN, a citizen of the United States, residing at Buffalo, in the county of Erie and State of New York, have invented a new, original, and ornamental Design for Spoons, of which the following is a specification, reference being had to the accompanying drawing, forming part thereof.

The figures are Figure 1 a front elevation

and Fig. 2 a rear elevation showing my new design.

I claim:

The ornamental design for a spoon, as shown.

FRANCIS M. VAN ETEN.
